(57) **CLAIM**

The ornamental design for a quickdraw, as shown and described.

DESCRIPTION

FIG. 1 is a perspective view of a quickdraw;

FIG. 2 is a front view thereof; and,

FIG. 3 is a right-side view thereof, the left-side view being a mirror image of the right-side view.

The rear portion of quickdraw, which is not seen in the photographs, forms no part of the claimed design.

1 Claim, 2 Drawing Sheets

FIG. 1

FIG. 2

FIG. 3
